UNITED STATES PATENT OFFICE.

ELLA I. COOLEY, OF COLDWATER, MICHIGAN.

SAFETY-BELT.

SPECIFICATION forming part of Letters Patent No. 579,818, dated March 30, 1897.

Application filed August 28, 1896. Serial No. 604,245. (No model.)

To all whom it may concern:

Be it known that I, ELLA I. COOLEY, of Coldwater, in the county of Branch and State of Michigan, have invented a new and Improved 5 Safety-Belt, of which the following is a full, clear, and exact description.

The object of my invention is to provide a belt especially adapted for use with infants or young children, being adapted particularly 10 for securing the child in a high chair or other seat, or in a carriage or similar vehicle, the belt being so constructed that while the child will be securely held in the chair or in a carriage the child will have such freedom as will 15 be necessary for its comfort, and whereby also the child may be held in an upright position when desired.

A further object of the invention is to provide a belt which will be exceedingly useful 20 to photographers when posing a young child.

The invention consists in the novel construction and combination of the several parts, as will be hereinafter fully set forth, and pointed out in the claim.

25 Reference is to be had to the accompanying drawings, forming a part of this specification, in which similar characters of reference indicate corresponding parts in both figures.

Figure 1 is a perspective view of the improved belt, and Fig. 2 is an edge view of the belt applied.

In carrying out the invention the belt proper, 10, is in the nature of a strap and is of the necessary length and width to be readily 35 passed around the waist of the child, for example. This belt is provided at one end with a buckle 11, the opposite end being adapted for attachment to the buckle. In connection with this waist-belt 10 a retaining or fastening strip 12 is employed, which is provided 40 with a buckle 13, and the retaining-strip 12 is connected with the waist-belt 10 through the medium of a strip 14 of rubber webbing or other elastic material, the belt and retaining-strip being connected at or near their 45 central portions.

The webbing 14 or elastic connection is preferably in loop form and is secured in any approved manner to the belt and to the said retaining-strap, as shown particularly in Fig. 50. 1. A second strap 15 is also used, which is preferably secured to the waist-belt 10, where it connects with the elastic webbing, and the strap 15 is likewise provided with a buckle 16.

When the child is placed in a high chair, 55 as shown in Fig. 2, the waist-belt 10 is buckled around the waist of the child, the connection being made a little to the rear about half-way between a point directly under the arm and the center of the back, and the retaining-strap 60 12 is buckled around the back of the chair. The child will thus be prevented from leaving the seat of the chair, while the elastic connection between the belt and the retaining-strap will permit the child to move to the 65 right or to the left, or a slight distance forward and rearward, the movements being sufficient for the comfort of the child. The child will also be prevented from unfastening the belt itself.

When the child is to be held in a steady position or upright in the chair, a strap 15 is buckled around a rung in the back of the chair. When the child is to be secured in a carriage, the retaining-strap 12 is passed 75 around the back of the carriage-body or around any other convenient support.

Having thus described my invention, I claim as new and desire to secure by Letters Patent—

80 A waist-belt, a retaining-strap, an elastic material secured to the waist-belt and the retaining-strap, and a second strap connecting the waist-belt and retaining-strap by which the movement of the said elastic material may 85 be restricted, as and for the purpose set forth.

ELLA I. COOLEY.
